(57) **CLAIM**

The ornamental design for a fan housing as shown and described.

DESCRIPTION

FIG. 1 is a top perspective view of a fan housing, showing my new design;

FIG. 2 is a bottom perspective view of the fan housing;

FIG. 3 is a front view of the fan housing, the rear view being a mirror image thereof;

FIG. 4 is a left side view of the fan housing, the right side view being a mirror image thereof;

FIG. 5 is a top view of the fan housing; and,

FIG. 6 is a bottom view of the fan housing.

Broken lines illustrate portions of the fan housing that form no part of the claimed design.
